UNITED STATES PATENT OFFICE.

COLEMAN Y. MCLEOD, OF CLARKSDALE, MISSISSIPPI.

DRAINAGE SYSTEM FOR CONCRETE CELLARS, VAULTS, BASEMENTS, &c.

1,320,256.

Specification of Letters Patent. Patented Oct. 28, 1919.

Application filed July 9, 1919. Serial No. 309,662.

To all whom it may concern:

Be it known that I, COLEMAN Y. MCLEOD, a citizen of the United States, residing at Clarksdale, in the county of Coahoma and 5 State of Mississippi, have invented new and useful Drainage Systems for Concrete Cellars, Vaults, Basements, &c., of which the following is a specification.

This invention has reference to draining 10 systems, and more particularly to a draining system employed in connection with cellars or vaults.

The primary object of the present invention is to provide a draining system which 15 will drain the soil or earth, in which the cellar is built, thereby insuring against the possibility of water or dampness seeping through the walls of the cellar.

A further object of the invention is to 20 provide means to efficiently drain the interior of the cellar, in the event that it becomes necessary to flush the cellar for sanitary purposes.

A still further object of the invention is 25 to drain the earth around the cellar, from various localities to a common basin, and carry off the drainage by means of a central discharge pipe.

With these and other objects in view 30 which will appear as the description proceeds, the invention resides in the details of construction hereinafter described and claimed, it being understood that changes in the precise embodiment of the invention 35 herein disclosed may be made within the scope of what is claimed, without departing from the spirit of the invention.

The invention is illustrated in the accompanying drawing, wherein:—

40 Figure 1 is a sectional view through a cellar with a draining system constructed in accordance with my invention, installed.

Fig. 2 is a plan view of the same, before the cellar floor is set up; and

45 Fig. 3 is a plan view of the cellar with the floor thereof constructed in accordance with the present invention.

Referring now to the drawing in detail, the reference characters 5 indicate side walls 50 of a cellar or vault, of suitable thickness and formed of plastic material, such as concrete. The floor or base 6, of the cellar is also formed of plastic material and is slightly inclined toward a common center as at 7, 55 where the same is formed with a substantially square opening 8, in which is posi-

tioned the drain tile 9 having the usual apertures 10 therein to permit of fluid passing therethrough and at the same time restricting the passage of particles which might 60 tend to clog or otherwise render the system inoperative.

Disposed under the opening 8 and centrally of the floor is a catch basin 11 which includes the base section 12 of concrete or 65 other suitable material, said base being apertured as at 13 to receive the drain pipe 14 which, in turn is provided with openings 15 in the end 16 thereof, which end 16, extends above the base 12 of the catch basin to receive water, while the opposite end 17, extends downwardly a suitable distance into the earth and is also provided with apertures 18 to exhaust fluid from said pipe 14.

The catch basin 11 also includes side walls 75 19 which extend upwardly from the base 12 and terminate flush with the underside of the cellar floor 6, to guard against water leaking through, at this point.

Openings 20 are disposed in the side walls 80 19, of the catch basin 11, and receive the inner ends 21 of the inclined drain tiles 22, said inner ends 21 thereof extend beyond the inner walls 19 to insure the discharge of water within the catch basin 11, the outer 85 ends 23 of said drain tiles 22, terminating at a point beyond the side walls 5 of the cellar, thereby draining the earth around the cellar, at a point beyond the vertical plane of the side walls 5, consequently, 90 draining the earth around the cellar, before the water or moisture can reach the walls 5 of the cellar.

Inclosed within the catch basin 11, and adapted to house the upper end 16 of the 95 drain pipe 14 is an auxiliary chamber having side walls 24 formed of suitable porous material to permit fluid to pass from the main catch basin 11 into the auxiliary chamber, the side walls 24 thereof being spaced 100 from the walls of the catch basin to permit water to collect therebetween, from where the water is carried off by the drain pipe 14.

Having thus described my invention, what I claim is:—

105 In a draining system for cellars having an inclined floor, and having a central drain opening, a catch basin disposed under the drain opening, said catch basin including outer walls, an interior auxiliary chamber 110 having walls of porous material spaced from the outer walls to provide a receiving

compartment, means for discharging fluid into the receiving compartment, a pipe having one of its ends extending into the auxiliary chamber, the opposite end thereof extending into the ground surface under the cellar, and each end of said pipe having openings to permit a flow of fluid therethrough.

In testimony that I claim the foregoing as my own, I have hereto affixed my signature 10 in the presence of two witnesses.

COLEMAN Y. MCLEOD.
